Patented Oct. 8, 1918.

UNITED STATES PATENT OFFICE.

FREDERICK H. LEWIS, OF MARION, CONNECTICUT.

VALVE-FACING TOOL.

1,280,774.

Specification of Letters Patent.

Patented Oct. 8, 1918.

Application filed February 10, 1917. Serial No. 147,818.

To all whom it may concern:

Be it known that I, FREDERICK H. LEWIS, a citizen of the United States, and a resident of Marion, county of Hartford, and State of Connecticut, have invented a certain new and useful Improvement in Valve-Facing Tools, of which the following is a full, clear, and exact specification.

This invention relates to a class of devices adapted to be used for repairing damaged valves.

My invention has for its object primarily to provide a tool designed to be employed for permitting valves to be quickly and easily faced as well as being trued to perfect accuracy by being re-faced especially when damaged by wear without requiring the work to be accomplished by expert workmanship as is incident to the methods ordinarily in use, and which is of an adjustable form to allow valves of various sizes and shapes to be repaired by the use of the tool. This is accomplished mainly by providing a frame in which is mounted an adjustable cutter for truing the head of the valve, and on the frame may be one or more bearings for removably supporting the valve so that its stem may be rotated to also revolve the head of the valve in contact with the cutter.

Other objects of the invention are to provide one or more adjustable clamps to releasably hold the valve stem in the bearings for rotation; to provide an adjustable stop on the frame for retaining the head of the valve in rotatable contact with the cutter; and to provide a separate handle adapted to be detachably applied on the valve stem whereby the valve may be manually rotated when being faced.

A further object of the invention is to provide a valve facing tool of a simple, efficient and durable form, and which is susceptible of being made in various sizes and shapes.

A practical embodiment of the invention is represented in the accompanying drawing forming a part of this specification in which similar characters of reference indicate corresponding parts in all the views, the said invention being more fully described hereinafter, and then pointed out in the claims at the end of the description.

In the drawing,

Figure 1 is a side elevation of one form

of valve facing tool embodying my invention. 55

Fig. 2 is a top plan of the tool.

Fig. 3 is an end view of the tool.

Fig. 4 is a detail sectional view taken on the line IV—IV of Fig. 1. 60

Fig. 5 is a fragmentary detail sectional view taken on the line V—V of Fig. 3, and

Fig. 6 is a section taken vertically through the cutter used in the tool. 65

The device, or valve facing tool has a frame 10 composed of a base-plate 11 of preferably a substantially rectangular shape, and projecting upwardly from one end of the base-plate is a standard, or bar 12 having an angularly bent arm 13 overhanging the base-plate, all of which may be made of any suitable material and in any desired shape and size. 70

Through the overhanging angular arm 13 of the standard 12 is a vertically disposed opening 13a in which is a cutter, as 14, adapted to be adjusted upwardly and downwardly relative to the base-plate 11 of the frame 10. The cutter has a substantially round rod-shaped body 15 of a length so that its lower end extends some distance below the arm 13 of the standard 12, while its upper end extends some distance above this arm of the standard. Projecting downwardly from the lower end of the body 15 of the cutter 14 is a blade 16 the lower free edge of which is cutaway on an incline, as at 17, which conforms to the beveled edge, as 18, of the head 19 of a valve 20 having a stem 21, the valve illustrated being of a well-known type. The 75

blade 16 may be provided by cutting-out or notching approximately one-half of the lower end part of the body 15 lengthwise and the inclined edge of the blade is bevel-sharpened to a knife edge for trimming the 80 beveled peripheral edge of the valve head 19 when being faced, as will be hereinafter more fully explained. A portion of the circular body lengthwise thereof is cutaway, as at 22, to provide a flat surface for being engaged by a set screw 23, which is threaded in an opening 24 in the arm 13 of the standard 12 for releasably locking the cutter 14 against accidental movement when adjusted in the arm of the standard 12. The purpose 85

of placing the cutter vertically is that in such a position the cutter will always engage the valve face in the center regardless of the 90

95

100

105

size of the head of the valve or its stem, whereas a cutter placed horizontally would vary its engagements with the valve according to the various sizes of its stems and heads. I have found in practice that my vertically disposed cutter attacking as it does a valve head centrally will do smoother and better work than a cutter horizontally disposed.

10 Extending upwardly from the base-plate 11 of the frame 10 may be one, or more vertically disposed spaced parallel posts 25 and 26 which may be provided on the frame so as to be stationary, or the posts may be 15 separate of the frame and connected thereto so as to be adjusted toward and from each other as well as being adjustable in spaced relation to and from the standard 12 of the frame of the tool. The adjustable posts 25 and 26 are of similar formations, and each post has a substantially rectangular body portion 27 with a substantially rectangular flange 28 projecting laterally from its lower end. Extending upwardly from the top of 25 one end of the body portion of each of the posts 25 and 26 is a vertically disposed arm 29 of approximately one-half the size or less, as viewed transversely, of the perimeter of the rectangular body of the post, and on the 30 upper end of the arm 29 of each post is a head 30 overhanging in spaced relation the second end of the body portion 27. By spacing the heads 30 from the body portions of the posts a recess, as 31, is provided in one 35 of the edges of each post. In the center of the second end of the top of the body portion 27 of each post is a bearing 32, and these bearings are preferably in the forms of substantially V-shaped notches disposed 40 crosswise of the body portion, while vertically through the head 30 of each post is a threaded opening 33 the center of which is on alignment with the center of the bearing of its respective post. The posts 25 and 26 45 are arranged on the base-plate 11 of the frame of the tool so that the apices of the V-shaped bearings 32 are on the same relative plane longitudinally as well as being in opposed relation to the cutting edge 17 of 50 the blade 16 of the cutter 14. The rectangular flanges 28 of the posts 25 and 26 will thereby be disposed transversely of the base-plate of the frame of the tool, and serving to releasably fasten the flanges to the base- 55 plate of the frame to permit the posts to be adjusted toward and from each other as well as toward and from the cutter 14, in the ends of the flange of each of the posts are elongated slots 34 and 35. Through the 60 slots 34 and 35 of the flange of each post are rotatably disposed finger or machine set screws, as 36 and 37, and these screws of each post are passed into threaded openings in the base-plate 11 of the frame. By tight- 65 ening the finger screws or set screws 36 and

37 the posts will be held on the frame against accidental displacement, and by loosening these set screws the post may be suitably adjusted on the base-plate relatively to the cutter 14 and also with respect to each other. 70

To face a valve by the use of the tool, for instance the form of valve, as shown at 20, the valve is arranged so that its stem 21 will be disposed in the recess 31 of the posts 25 and 26 for being seated in the V-shaped 75 bearings 32 and so that the beveled periphery of the head 19 of the valve will be in contact with the inclined cutting edge 17 of the blade of the cutter 14, as illustrated in Fig. 1. The free end of the stem of the 80 valve will then extend some distance beyond one end of the tool, and to rotate the valve so that the beveled periphery of its head will be properly faced by being trimmed by the cutter 14, I may employ any desired 85 form of implement, though I prefer to use a separate crank handle, as 38. The crank handle 38 may be of a well-known form, as shown, having an apertured sleeve, as 39, which is removably guided on the free end 90 part of the stem of the valve, and threaded in an opening in this sleeve is a set screw 40 for being rotatably guided into engagement with the stem of the valve when the handle is applied thereon. The handle 38 will then 95 be tightly held on the stem of the valve for manual rotation to revolve the head of the valve in contact with the cutter for being faced.

Serving to releasably hold the valve stem 100 in the bearings 32 for rotation, adjustable clamps 41 and 42 are provided. The clamps 41 and 42 are similarly formed, and each clamp has a threaded bolt 43. One of the bolts of each clamp is screwed through the 105 threaded opening 33 of the head 30 of each of the posts 25 and 26, and these bolts are of lengths so that their lower ends extend below the heads of the posts into the recesses 31 thereof as well as extending some distances above the heads while on the upper ends of each bolt is a head, as 44, to allow the bolts to be easily screwed upwardly and downwardly in the heads of the posts for varying the spacing between their lower 110 ends with relation to the bearings 32 of the posts. On the lower end of the bolt 43 of each of the clamps is a rotatably movable block 45, and these blocks are preferably substantially 115 rectangular in shapes. Each of the blocks 45 has a recess 46 in its top surface, and in these recesses are disposed the lower ends of the bolts 43, the recesses being of somewhat greater diameters than the bolts to allow the blocks to be revolvably movable thereon. Through a hole in one of the side walls of each of the blocks 45 is driven a pin 46^a which passes into the recess 46 and into an annular recess 47 provided at the end of the bolt which is disposed in the recess, these 120 125 130

pins being of sizes so as to move in the annular recesses of the bolts when the blocks are revolubly moved. When the valve is arranged in the tool so that its stem is disposed in the V-shaped bearings 32 of the adjustable posts 25 and 26, as above explained, the clamps 41 and 42 are operated to hold the stem rotatably in the bearings by turning the heads 44 to revolve the bolts 43 for moving the blocks 45 into engagement with the top of the stem of the valve, and the crank handle 38 is revolved to rotate the valve for facing the valve.

In order to hold the head of the valve in rotatable contact with the cutter 14, an adjustable stop 47 is provided. The adjustable stop 47 has a concaved circular head, or plate 48 adapted to be moved into contact with the head of the valve, and in an opening centrally of this plate is rotatably held one end of a threaded bolt, as 49. In the standard 12 of the frame 10 of the tool is a threaded opening 50 the center of which is on longitudinal alinement with the center 25 of the head of the valve, and in this opening is screwed the bolt 49 so that the concaved face of its head 48 will be in opposed relation to the head of the valve, while on the second end of the bolt is a rigid 30 head 51 to allow the bolt to be readily rotated. When this bolt is adjustably rotated accordingly the head 48 will be moved into contact with the head of the valve for releasably retaining the valve head in engagement with the cutter 14 when being faced, and the concaved head of the bolt being revoluble thereon it will also revolve with the rotation of the valve when turned by the crank handle 38. Thus by the use 35 of this tool valves when damaged by wear, or otherwise may be easily and properly refaced without requiring skilled workmanship, and as many forms of valves are provided with shouldered stems, the adjustable posts 25 and 26 will permit of their accommodation in the tool. Also by providing the adjustable cutter 14 valve heads of various diameters may be readily faced by the use of the tool.

50 In the foregoing description, I have embodied the preferred form of my invention, but I do not wish to be understood as limiting myself thereto, as I am aware that modifications may be made therein without departing from the principle, or sacrificing any of the advantages of this invention therefore I reserve to myself the right to make such changes as fairly fall within the scope thereof.

60 Having thus described my invention, I claim as new and desire to secure by Letters Patent:—

1. A valve facing tool, comprising a base-plate having a cutter adjustably supported above the base-plate, posts on the base-plate

adjustable toward and from each other, bearings in the posts whereby the stem of a valve may be removably and revolubly held so that the head of the valve will be in movable contact with the cutter, means on each post to releasably retain the stem of the valve in the bearings, and a separate handle adapted to be detachably fastened on the stem of the valve so that the valve may be manually rotated.

2. A valve facing tool, comprising a substantially rectangular base-plate having an upwardly projecting standard, a cutter adjustably supported on the standard above the base-plate, posts on the base-plate in spaced relation to the standard, and said posts being adjustable toward and from each other as well as being adjustable toward and from said standard, bearings in the posts whereby the stem of a valve may be removably and revolubly held so that the head of the valve will be in movable contact with said cutter, and means on each post to releasably retain the stem of the valve in the bearings.

3. A valve facing tool, comprising a substantially rectangular base-plate having an upwardly projecting standard, a cutter adjustably supported on the standard above the base-plate, posts on the base-plate in spaced relation to the standard, and said posts being adjustable toward and from each other as well as being adjustable toward and from said standard, bearings in the posts whereby the stem of a valve may be removably and revolubly held so that the head of the valve will be in movable contact with said cutter, means on each post to releasably retain the stem of the valve in the bearings, and a separate handle adapted to be detachably fastened on the stem of the valve so that the valve may be manually rotated.

4. A valve facing tool, comprising a substantially rectangular base-plate having on one of its ends an upwardly projecting standard with an apertured arm overhanging the base-plate, a blade adjustable in the aperture of the arm, having a beveled cutting edge in opposed relation to the standard, means for releasably locking the blade to the arm of the standard when adjusted, posts on the base-plate in spaced relation to the standard, and said posts being adjustable toward and from each other as well as being adjustable toward and from said standard, bearings in the posts whereby the stem of a valve may be removably and revolubly held so that the head of the valve will be in movable contact with the cutting edge of said blade, and means on each post to releasably retain the stem of the valve in the bearings.

5. A valve facing tool, comprising a substantially rectangular base-plate having on one of its ends an upwardly projecting

standard with an apertured arm overhanging the base-plate, a blade adjustable in the aperture of the arm, having a beveled cutting edge in opposed relation to the standard, means for releasably locking the blade to the arm of the standard when adjusted, posts on the base-plate in spaced relation to the standard, and said posts being adjustable toward and from each other as well as being adjustable toward and from said standard, bearings in the posts whereby the stem of a valve may be removably and revolvably held so that the head of the valve will be in movable contact with the cutting edge of said blade, means on each post to releasably retain the stem of the valve in the bearings, and a separate handle adapted to be detachably fastened on the stem of the valve so that the valve may be manually rotated.

6. A valve facing tool, comprising a base-plate having an upwardly projecting standard with an apertured arm overhanging the base-plate, a blade adjustable in the aperture of the arm, having a beveled cutting edge in opposed relation to the standard, means for releasably locking the blade to the arm of the standard when adjusted, posts on the base-plate in spaced relation to the standard, and said posts being adjustable toward and from each other as well as being adjustable toward and from said standard, bearings in the posts whereby the stem of a valve may be removably and revolvably held so that the head of the valve will be in movable contact with the cutting edge of said blade, means on each post to releasably retain the stem of the valve in the bearings, and means on the standard of the base, adjustable for revolvably holding the head of the valve in revolute engagement with the cutting blade.

7. A valve facing tool, comprising a base-plate having an upwardly projecting standard with an apertured arm overhanging the base-plate, a blade adjustable in the aperture of the arm, having a beveled cutting edge in opposed relation to the standard, means for releasably locking the blade to the arm of the standard when adjusted, posts on the base-plate in spaced relation to the standard, and said posts being adjustable toward and from each other as well as being adjustable toward and from said standard, bearings in the posts whereby the stem of a valve may be removably and revolvably held so that the head of the valve will be in movable contact with the cutting edge of said blade, means in each post to releasably retain the stem of the valve in the bearings, means on the standard of the base, adjustable for revolvably holding the head of the valve in revolute engagement with the cutting blade, and a separate handle adapted to be detachably fastened on

the stem of the valve so that the valve may be manually rotated.

8. A valve facing tool, comprising a substantially rectangular base-plate having on one of its ends an upwardly projecting standard with an apertured arm overhanging the base-plate, a cutter adjustable in the aperture of the arm, posts on the base-plate in spaced relation to the standard for removably and revolvably supporting a valve, and said posts being adjustable toward and from each other as well as being adjustable toward and from said standard, means in each post to releasably retain the stem of the valve on the posts, and means on the standard of the base, adjustable for revolvably holding the head of the valve in engagement with the cutting blade.

9. A valve facing tool, comprising a substantially rectangular base-plate having on one of its ends an upwardly projecting standard with an apertured arm overhanging the base-plate, a cutter adjustable in the aperture of the arm, posts on the base-plate in spaced relation to the standard for revolvably supporting a valve, and said posts being adjustable toward and from each other as well as being adjustable toward and from said standard, means in each post to releasably retain the stem of the valve on the posts, means on the standard of the base, adjustable for revolvably holding the head of the valve in revolute engagement with the cutting blade, and a separate handle adapted to be detachably fastened on the stem of the valve so that the valve may be manually rotated.

10. A valve facing tool, comprising a substantially rectangular base-plate having on one of its ends an upwardly projecting standard with an apertured arm overhanging the base-plate, a beveled cutter adjustable in the aperture of the arm in opposed relation to the standard, means for releasably locking the cutter to the arm of the standard when adjusted, posts on the base-plate adjustable toward and from said standard whereby the stem of a valve may be removably and revolvably held so that the head of the valve will be in movable contact with the cutting edge of said cutter, and means on the standard of the base, adjustable for revolvably holding the head of the valve in revolute engagement with the cutter.

11. A valve facing tool, comprising a substantially rectangular base-plate having on one of its ends an upwardly projecting standard with an apertured arm overhanging the base-plate, a beveled cutter adjustable in the aperture of the arm, having a beveled cutting edge in opposed relation to the standard, means for releasably locking the cutter to the arm of the standard when

adjusted, posts on the base-plate adjustable toward and from said standard whereby the stem of a valve may be removably and revolvably held so that the head of the valve will 5 be in movable contact with the cutting edge of said cutter, means on the standard of the base, adjustable for revolvably holding the head of the valve in revolvable engagement with the cutter, and a separate handle 10 adapted to be detachably fastened on the

stem of the valve so that the valve may be manually rotated.

This specification signed and witnessed this seventh (7th) day of February, A. D. 1917.
